GLUE GUN

Robert C. Warren, Los Angeles, Calif., assignor to
John P. Fox, Studio City, Calif.

Application October 2, 1948, Serial No. 52,507

6 Claims. (Cl. 15—127)

This invention relates to liquid ejectors, typified by a gun for dispensing liquid or plastic adhesive material such as glue, and pertains particularly to such units which are operated by compressed air and contain a valve adapted to release the glue intermittently as the nozzle is applied to successive workpieces.

It is an object of the invention to provide such a glue gun which releases glue upon pressure of the nozzle against a workpiece. Such a nozzle can be held in the hand and moved from one point of application to another without the glue dripping between ejections. The nozzle is particularly adapted to supply glue or other adhesive to the sides of indentures in the workpiece such as dowel holes, grooves or joints, etc., which is more effective than flooding the floor of the opening with the adhesive before inserting the dowel or panel to be attached.

Other objects and advantages of the invention will be apparent from the following description and claims, the novelty consisting in the features of construction, combination of parts, the unique relations of the members and the relative proportioning, disposition, and operation thereof, all as more completely outlined herein and particularly pointed out in the appended claims.

In the drawings, which form part of the present specification:

Figure 1 is a vertical sectional view of a portable hand pump and glue container connected to one form of my glue gun, shown in side elevation;

Figure 2 is an enlarged view of the glue gun of Figure 1, shown in longitudinal section;

Figure 3 is a detail view of the nozzle of the glue gun of the preceding figures, inserted in operating position in a dowel hole;

Figure 4 shows another form of my glue gun with the valve section shown in longitudinal section and the nozzle seen in side elevation in a groove to which it delivers glue; and

Figure 5 is an end view of the nozzle of Figure 4 in working position in a groove.

My glue gun 10 is particularly adapted to be attached to a flexible glue conduit 12 so that it can be grasped in the hand and drawn along a groove or inserted in successive dowel holes or the like to which it is desired to deliver glue. Alternately however it may be mounted on a rigid conduit and the workpieces moved in relation to the glue nozzle if desired.

The glue gun is adapted for use with a source of glue under pressure so that intermittent release of the valve in the nozzle end of the gun will allow the glue to flow out the nozzle. Opening of the valve is effected by pressure of the nozzle against the workpiece as will be explained shortly. As illustrated in Figure 1, the gun 10 by its feed conduit 12 is connected to a portable container 14 which holds glue 16 in its lower portion and has an air chamber 18 above the level of the glue. A tubular neck 20 arises centrally from the air chamber and in communication therewith, and serves to house a reciprocating piston 22 connected at its upper face to a piston rod 24 which extends upward thru the cylinder cap 26 and its guide boss 28 to the exterior where it is attached to a hand lever 30 fulcrumed at 32 to an upright arm 34, the lower extremity of which is bent inward at 36 to connect to the neck 20. A one-way air inlet valve 38 is located near the top of the neck 20 while a similar valve 40 is seated in the piston 22 to permit the latter to travel freely upward in the neck 20

when the valve 38 is closed.

Thus by pumping the lever 30 for a short time, a considerable air pressure can be built up in the chamber 18 which acts against the upper surface of the glue 16 to force it thru the conduit 12 whenever the glue is allowed to pass out the nozzle. In this connection it should be noted that the air is not mixed with the glue—the glue is not sprayed out—and it is not necessary to pump the lever 30 at the same time that the glue is being released from the gun. Alternately, of course, suitable stationary and/or automatic sources of pressurized fluid can be used in place of the portable hand pump.

In the form of glue gun 10 illustrated in Figures 1-3, there is provided an elongated handle 42 centrally relieved at 44 for grasping, and drilled from each end to provide a continuous longitudinal passage for the glue therethru, having a principal bore 46 extending thru most of the body and generally corresponding in diameter to the supply line 12, and a smaller outlet or terminal bore 48. The inlet end may be internally threaded at 50 to receive the end of the supply line which is here equipped with a lock nut 52.

The further, tapered end 54 of the handle is provided with a centered, open-ended, internally threaded socket 56 within which different sized nipples 58 may be mounted. The nipple or nozzle end is formed with a threaded neck 60 dimensioned for reception in the socket 56, a flared shoulder portion 62 adapted to abut against the tapered end 54 of the handle, and a tubular extension 64 having a large longitudinal bore 61 extending from the attachment end nearly to the opposite end, and a smaller axial bore 68 running inward from the free end to join the larger bore 61.

At the outer end of the larger bore 61 its diameter decreases arcuately to provide a seat for a ball valve 70 which is held in place by a helical spring 72 within the bore, its opposite end pressing against a washer 73 in the base of the socket 56. Within the smaller bore 68 and projecting out from the end thereof is a striker 74 having a radially enlarged head 76 disposed within the end of the smaller bore so as to allow it to press back the ball 70 upon further insertion of the striker in its channel and also to keep the striker from falling out of the nozzle when it moves in the opposite direction. Outwardly from the ball valve 70 are an opposing pair of lateral glue outlets 78 connected at their mouths by a peripheral groove 80.

Accordingly, when the end of the nozzle 58 is inserted in a dowel hole 82 (Figure 3) to which it is desired to supply glue, upon the striker 74 being pushed in by contact with the bottom of the hole, its head 76 presses back the ball 70 to allow glue to flow around it and thru the outlet 78, filling the groove 80 and adhering to the side of the hole 82. When the nozzle is withdrawn, the bead of glue about the groove 80 is wiped off along the sides of the dowel hole, which is where it is desired to locate it rather than in the bottom of the hole. Consequently, the nozzle can be inserted in such a hole and withdrawn almost immediately, thus proceeding from one hole to another with great rapidity and without dripping glue between holes. Externally, the tubular portion 64 of the nozzle may be of any configuration such as annular or polygonal to correspond to the opening in which it is desired to deliver glue, and due to its ready attachment and detachment from the handle, it can be provided in a series of different sizes to fit various size dowel holes.

In the embodiment of the invention illustrated in Figures 4 and 5, there is provided a closed-end nozzle having a bevelled tip 84 and lateral apertures 86 for delivering glue to the sides of grooves when drawing the tip along a groove 87 on its bevelled surface. The nozzle is attached to a valve assembly employing a rigid conduit section 88 and a flexible conduit section 90 with an operating rod 92 disposed within the conduit and extending from the rigid section into the flexible section. A spherical end 94 of the rod within the rigid section is seated in a corresponding socket 96 of a cylindrical boss 98 of an annular valve plate 100 which is normally held seated across the outlet line 102 by a coil spring 104 the other end of which abuts against an internal shoulder 106 of

the rigid conduit segment. About the periphery of the valve plate is a segmented or transversely interrupted bead 108 extending radially nearly to the inner face of the conduit. The opposite end of the rigid section is radially restricted at 110 and externally serrated at 112 for attachment thereover of the flexible portion. The free end of the operating rod carries an enlarged knob 114.

Accordingly when the bevelled tip is pressed against the bottom of a groove 87, movement of the flexible conduit 90 against the knob 114 causes the rod 92 to fulcrum at 110 and its opposite ball end 94 to unseat the valve 100, allowing glue to pass between the bead segments 108 and thru the escape channel 102 to the outlets 86. As the nozzle is drawn along the groove 87, glue is supplied to the sides thereof, so as to retain for example a panel subsequently inserted in the groove. As soon as bending pressure is released from the nozzle (or more accurately from the flexible section) the spring 104 seats the valve 100.

It will thus be seen that I have produced an automatic, hand-manipulated glue gun which has the particular advantage of delivering glue to the sides of a groove or hole of a workpiece in response to the pressure of the nozzle thereagainst. While two presently preferred embodiments are here shown and described in some detail, it is to be understood that various modifications may be made therein within the scope of the invention as hereafter defined, it being my intention to claim the invention broadly within the limitations of the prior art.

I claim:

1. In a hand-manipulated glue gun having a flexible conduit connected to a source of glue under pressure, a handle having a longitudinal passage therein, one end of said passage being connected to said conduit, a tubular nozzle connected to the other end of said handle, said handle and said nozzle being substantially coaxial, the free end of the nozzle being formed with a groove extending around at least a portion of the nozzle periphery and communicating through an orifice with said passage so as to provide an outlet for glue, means defining a valve seat between said orifice and said conduit, a check valve ball disposed within said nozzle on the high pressure side of said valve seat and resilient means disposed normally to urge said ball seated against said valve seat so as to prevent outward passage of glue therethrough, and a longitudinally displaceable striker projecting generally axially from the free end of the nozzle, the inner end of said striker being positioned to engage said ball to unseat same from said valve seat upon the striker being pressed into the nozzle by engagement with a work piece.

2. In a hand-manipulated glue gun having a flexible conduit connected to a source of glue under pressure, a handle having a longitudinal passage therein, one end of said passage being connected to said conduit, a tubular nozzle connected to the other end of said handle, said handle and said nozzle being substantially coaxial, the free end of the nozzle being formed with a circular groove in the side wall thereof and a plurality of orifices that establish communication between said passage and said groove so as to provide a plurality of outlets for glue, means defining a valve seat between said orifices and said conduit, a check valve between said orifices and said conduit, said check valve normally being closed so as to prevent outward passage of glue therethrough, and a movable striker projecting outwardly from the free end of the nozzle and having its inner end adapted to open said valve when the outer end of said striker engages a work piece.

3. In a glue gun having means for delivering glue under pressure, a tubular nozzle for dispensing such glue, one end of said nozzle being adapted to receive glue under pressure, the other end of the nozzle being formed with a peripheral groove and an orifice providing communication between said groove and the interior of said nozzle so as to provide an outlet for glue, a check valve between

said orifice and said one end, said check valve normally being closed so as to prevent outward passage of glue therethrough, and a movable striker projecting outwardly from the free end of the nozzle and having its inner end adapted to open said valve when the outer end of said striker engages a work piece.

4. In a hand-manipulated glue gun, having means for delivering glue under pressure, a tubular nozzle having a passage extending thereinto from one end thereof, said one end being adapted to receive glue under pressure, the nozzle having a plurality of lateral orifices spaced about the periphery thereof and between the ends of said nozzle, said orifices communicating with said passage so as to provide a plurality of outlets for glue, the passage being enlarged between said one end and said orifices to form a valve seat therein, a check valve ball disposed within said nozzle on the high pressure side of said seat, resilient means for urging said ball into seating engagement with said valve seat so as to prevent outward passage of glue therethrough, said nozzle being formed with a reduced bore at the other end thereof, and a striker extending through said reduced bore into said passage and provided with an enlarged head at the inner end thereof, said striker being movable into and out of said passage, said striker unseating said ball from said seat to permit outward passage of glue therethrough when said striker is pressed into said passage.

5. In a hand-manipulated glue gun, having means for delivering glue under pressure, a tubular nozzle having a passage extending thereinto from one end thereof, said one end being adapted to receive glue under pressure, the nozzle being formed with a peripheral groove on the side thereof and an orifice providing communication between said groove and said passage so as to provide an outlet for glue, the passage being enlarged between said one end and said orifice to form a valve seat therein, a check valve ball disposed within said nozzle on the high pressure side of said seat, resilient means for urging said ball into seating engagement with said valve seat so as to prevent outward passage of glue therethrough, said nozzle being formed with a reduced bore at the other end thereof, and a striker extending through said reduced bore into said passage, said striker being movable into and out of said passage, said striker unseating said ball from said seat to permit outward passage of glue therethrough when said striker is pressed into said passage.

6. In a hand-manipulated glue gun, having means for delivering glue under pressure, a tubular nozzle having a passage extending thereinto from one end thereof, said one end being adapted to receive glue under pressure, the nozzle being formed with an encircling groove between the ends thereof and a plurality of orifices that establish communication between said passage and said groove so as to provide an outlet for glue, the passage being enlarged between said one end and said orifice to form a valve seat therein, a check valve ball disposed within said nozzle on the high pressure side of said seat, resilient means for urging said ball into seating engagement with said valve seat so as to prevent outward passage of glue therethrough, said nozzle being formed with a reduced bore at the other end thereof, and a striker extending through said reduced bore and provided with an enlarged head at the inner end thereof, said striker being movable into and out of said passage, said striker unseating said ball from said seat to permit outward passage of glue therethrough when said striker is pressed into said passage.
